M. P. HOLMES

MINING APPARATUS

Filed Sept. 5, 1924

UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING APPARATUS.

Application filed September 5, 1924. Serial No. 736,153.

My invention relates to mining apparatus. An object of my invention is to provide an improved mining apparatus and more particularly to provide a wheeled mining apparatus adapted to operate while mounted on a trackway. Another object of my invention is to provide a mining machine transport and cutting truck of an improved construction. Still another object of my invention is to provide an improved mining machine transport and cutting truck having improved driving means therefor whereby the same may be driven at different speeds directly from the mining machine feeding mechanism. A still further object of my invention is to provide an improved mining machine transport and cutting truck having improved means for swinging the cutting mechanism whereby the same may be swung at different speeds directly from the mining machine feeding mechanism. A still further object of my invention is to provide an improved mining machine transport and cutting truck having reverse mechanism thereon and improved cutter bar swinging mechanism whereby the truck may be driven and the bar swung in opposite directions relative to a trackway at fast or slow speeds directly from the mining machine feeding mechanism. A still further object of my invention is to provide an improved transport and cutting truck to which a unitary mining machine is adapted to be secured, thereby permitting the mining machine to cut on the track and wherein the mining machine may be bodily removed from the truck and cut on the mine bottom in accordance with the long wall system of cutting. These and other objects and advantages of my invention will, however, hereinafter more fully appear.

In the accompanying drawings I have shown for purposes of illustration one form which my invention may assume in practice.

In these drawings,—

Fig. 1 is a side elevation, partially in central vertical longitudinal section, of my improved truck with a unitary mining machine secured thereto adapted to operate as a mounted cutter.

Fig. 2 is a plan view, partially in section, of the machine shown in Fig. 1, the cutter bar being shown in a plurality of positions.

Fig. 3 is a detail sectional view of a por-

tion of my improved truck driving mechanism.

Fig. 4 is a detail sectional view through one of the frictional feed controlling devices.

In the illustrated form of my invention I have provided a truck frame 1 provided with axle boxes 2 in which axles 3 are journaled, to which axles wheels 4 are suitably secured being adapted to move relative to a trackway 5. A cylindrical guiding plate 6 is suitably secured to the frame 1 and is provided with an inwardly projecting flange 7 forming a groove in which an annular gib 8 is disposed. The gib 8 is formed on a swivel housing and machine supporting frame member 9. A guiding frame 10 is suitably secured, as at 11, to the housing 9. The guiding frame 10 is adapted to receive a self-propelled flexibly fed unitary mining machine generally designated 12 of the general type described and claimed in my copending application Ser. No. 619,839, filed Feb. 19, 1923, the mining machine being of the long-wall type adapted to slide on its own bottom on the mine bottom and having an elongated frame which consists of a feed frame section 13, a motor section 14 and a cutter frame section 15, the frame sections 13, 14 and 15 being secured together in any suitable manner. Herein it will be noted that the frame sections 13, 14 and 15 present parallel plane surfaces 16 and 17 upon which the mining machine is selectively adapted to slide during cutting, that is, when the machine is being used as an under cutter or is inverted and used as an over cutter. The cutting frame section 15 also carries a cutter bar 18 pivoted thereon, as at 19, on a vertical axis and provided with an endless cutter bit carrying cutter chain 20 which is adapted to be circulated about the outer edges of the cutter bar in a well known manner when driven through suitable power connections (not shown) from the driving motor. The cutter bar 18 is as shown herein also adapted to be swung or slued about its pivot 19 into opposite lateral positions relative to the machine frame and at right angles thereto or into alignment with the longitudinal axis of the machine frame and as shown herein is also adapted to be locked in these positions by means of a rotatable pin 21 adapted to register with suitably located notches 22 formed in the flanged portion of the cutting frame

15. The plane surface 16 of the mining machine frame is detachably secured as by bolts 23 to the housing 9. It will herein be noted that the machine may be inverted and the plane surface 17 secured to the housing 9 in a similar manner when it is desired to vary the plane of the cutter bar.

A feed operating member or sprocket 24 is also herein suitably journaled on a longitudinally extending horizontal axis on the rear end of the feed frame section 13 and adapted to cooperate with a flexible feed chain 25, indicated by chain lines in Fig. 2, during sluing of the cutter bar 18 about its pivot 19 or to feed the machine bodily on the mine bottom when the machine is removed from the truck and acting as a long-wall cutter. The feed sprocket 24 is herein, as in my previously mentioned application, adapted to be driven at a slow or cutting speed through one train of mechanism (not shown) under the control of a frictional controlling device of the disc clutch type, generally designated 26 and through another train (not shown) at a fast speed in the opposite direction under the control of a similar friction controlling device, generally designated 27, these controlling devices 26 and 27 forming a part of the feeding mechanism 30 of the mining machine mentioned above and being adapted to operate alternatively as described in my copending application under control of a controlling member or hand wheel 28 disposed at the rear end of the frame section 13. Each of these frictional controlling devices comprises a longitudinally extending driving shaft 29 provided with a pinion 30 which meshes with an internal gear 31 formed on the friction housing member 32. Friction discs 33 are secured to the housing member 32 and to a member 34 secured, as by a key 35, to a shaft 36 which drives the feed operating member 24. The friction clutch is adapted 45 to be controlled by an operating member 37 which is adapted to be actuated through suitable mechanism by means of the hand wheel 28.

In my improved construction it will be observed that an annular member 38 is suitably secured to, by means of a bolt connection 39, and rotatable with the feed sprocket 24 and that this member 38 is provided with internal clutch teeth 40 adapted to cooperate with external clutch teeth 41 formed on a longitudinally extending horizontal shaft 42 journaled in bearings 43 suitably secured to the guiding frame 10. The shaft 42 has secured thereto at its rear end, a spur pinion 44 which meshes with a spur gear 45 suitably secured to an elongated longitudinally extending shaft 46 disposed parallel with the shaft 42 and journaled in bearings 47 and 48 carried by the guiding frame 10 and housing 9, respectively. A bevel pinion 49

is adapted to be connected with the shaft 46 by means of a sliding jaw clutch 50 and this pinion meshes with a large bevel gear 51 which is rigidly secured as by bolts 52 to a part of the truck frame 1. The shaft 46 is provided with a reduced portion 53 which extends within the housing 9 and has loosely journaled thereon a pair of bevel gears 54 which are adapted to be selectively connected to the shaft 46 by means of a sliding jaw clutch 55 and are adapted to drive a bevel gear 56 in opposite directions at the will of the operator. The gear 56 is secured to a vertically disposed shaft 57 journaled in a bearing 58 and disposed coaxially with the axis of the swivel housing 9 and has secured thereto at its lower end a bevel gear 59 which constantly meshes with a bevel gear 60 suitably secured to the longitudinally extending shaft 61 suitably journaled in a bearing 62 carried by the truck frame 1. The shaft 61 has secured thereto at its forward end a bevel gear 63 which meshes with a bevel gear 64 suitably secured to the front axle 3 of the truck. The jaw clutches 50 and 55 are provided with operating cranks 65 and 66 to which longitudinally extending operating rods 68 and 69 are suitably secured and which are adapted to be actuated by means of hand levers 70 and 71 pivoted adjacent the rear end of the guiding frame 10.

In the use of my improved mining apparatus it will be observed that the truck may be driven relative to the trackway 5 at a fast or at a slow speed in opposite directions directly from the mining machine feeding mechanism per se under the control of the feed controlling frictional devices 26 and 27 and may be also driven in reverse of these directions by means of the reverse gears 54 and the controlling clutch 55, any desired variance of these speeds of course also being obtainable. It will also be noted that the clutch 55 may be thrown out into its inoperative position and the clutch 50 thrown in, thus rotating the bevel pinion 49 relative to the stationary bevel gear 51 causing the machine and consequently the cutter bar to be bodily swiveled relative to the trackway at a slow or cutting speed in one direction and at a fast speed in the opposite direction, likewise under the control of the frictional controlling devices 26 and 27. It will also further be noted that if desired the feed chain 25 may be secured to the cutter bar and the bar swung into either of the lateral positions as indicated in dotted lines in Fig. 2. It will also be noted that by means of the reverse gears 54 the truck may be driven in either direction relative to the trackway at either a fast or at a slow speed. If desired a suitable skid, not shown, may be placed in front of the truck and the bolts 23 may be removed, permitting the machine to

be unloaded from the truck and to operate on its own bottom on the mine bottom selectively as an under cutter or an over cutter and in accordance with the longwall system of mining.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a mining apparatus, a wheeled truck frame, a mining machine having opposed plane surfaces upon which it is disposable and which are constructed to constitute skid surfaces to support the machine for sliding movement during cutting, said machine being constructed to cut when sliding directly upon a mine bottom on either of such surfaces, and means to swivel such machine relative to said frame from said machine when the latter is disposed in either position on said frame.

2. In a mining apparatus, a wheeled truck frame, a mining machine swivelly mounted thereon and operable to cut in different horizontal planes when supported in inverted positions, and self-contained means to swivel said machine relative to said frame from said machine when the latter is disposed in either position.

3. In a mining apparatus, a truck frame having running gear, a mining machine having opposed plane surfaces upon which it is disposable and constructed to cut when sliding directly upon the mine bottom on either of such surfaces, and means to swivel such machine relative to said frame and to propel said running gear both from said machine when the latter is disposed in either position on said frame.

4. In a mining apparatus, a truck frame having running gear, a mining machine swivelly mounted thereon, said machine being of the type adapted to slide on the mine bottom during cutting and having a plurality of surfaces each adapted to support the machine and which are constructed to constitute skid surfaces upon which the machine may slide during cutting, said machine further having provision whereby it may cut in different planes when supported on said different surfaces, and means to swivel said machine relative to said frame from said machine when the latter is disposed on said truck frame on any of said surfaces.

5. In a mining apparatus, a truck frame having running gear, a mining machine swivelly mounted thereon, said machine being of the type adapted to slide on the mine bottom during cutting and having a plu-

rality of surfaces each adapted to support the machine and which are constructed to constitute skid surfaces upon which the machine may slide during cutting, said machine further having provision whereby it may cut in different planes when supported on said different surfaces, and means to swivel said machine relative to said frame from said machine when the latter is disposed on said truck with any of said surfaces in a horizontal plane.

6. In a mining apparatus, a truck frame having running gear, a mining machine swivelly mounted thereon, said machine being of the type adapted to slide on the mine bottom during cutting and having a plurality of surfaces each adapted to support the machine and further having provision whereby it may cut in different planes when supported on said different surfaces, and means to drive said running gear from said machine when the latter is disposed on said truck frame on any of said surfaces.

7. In a mining apparatus, a truck frame having running gear, a mining machine swivelly mounted thereon, said machine being of the type adapted to slide on the mine bottom during cutting and having a plurality of surfaces each adapted to support the machine and further having provision whereby it may cut in different planes when supported on said different surfaces, and means to drive said running gear from said machine when the latter is disposed on said truck with any of said surfaces in a horizontal plane.

8. In a mining apparatus, a truck frame having running gear, a mining machine swivelly mounted thereon, said machine being of the type adapted to slide on the mine bottom during cutting and having a plurality of surfaces each adapted to support the machine and further having provision whereby it may cut in different planes when supported on said different surfaces, and means to swivel said machine relative to said frame and to propel said running gear from said machine when the latter is disposed on said truck frame on any of said surfaces.

9. In a mining apparatus, a truck frame having running gear, a mining machine swivelly mounted thereon, said machine being of the type adapted to slide on the mine bottom during cutting and having a plurality of surfaces each adapted to support the machine and further having provision whereby it may cut in different planes when supported on said different surfaces, and means to swivel said machine relative to said frame and to propel said running gear from said machine when the latter is disposed on said truck with any of said surfaces in a horizontal plane.

10. In a mining apparatus, a truck having

- running gear, a mining machine receiving frame pivoted on said truck for movement upon a vertical axis, driving gearing for said running gear on said truck and including a shaft rotatable on said vertical axis, and driving gearing for said shaft including a shaft extending radially relative to said axis and moving with said frame on pivotal movement of the latter on the vertical axis.
11. In a mining apparatus, a truck having running gear, an elongated mining machine receiving frame pivoted on said truck for movement upon a vertical axis, driving gearing for said running gear on said truck and including a shaft rotatable on said vertical axis, and driving gearing for said shaft including a shaft extending longitudinally of said frame.
12. In a mining apparatus, a truck having running gear, a mining machine receiving frame pivoted on said truck for swinging movement upon a vertical axis, a gear element mounted on said truck with its center in said axis, a shaft rotatable on an axis perpendicular to said first mentioned axis, and rotatable in bearings stationary relative to said frame, a gear coaxial with and rotatable with said shaft and engaging said gear element, and means for effecting rotation of said shaft.
13. In a mining apparatus, a truck having running gear, an elongated mining machine receiving frame pivoted on said truck for swinging movement upon a vertical axis, a gear element mounted on said truck with its center in said axis, a shaft rotatable on an axis extending longitudinally of said frame and rotatable in bearings stationary relative to said frame, a gear on and rotatable with said shaft and engaging said gear element, and means for effecting rotation of said shaft.
14. In a mining apparatus, a wheeled truck frame, a mining machine swivelly mounted thereon operable to cut in different planes to which the axis of swiveling is perpendicular when supported in inverted positions, and means to swivel said machine relative to said frame from said machine at either a predetermined cutting speed or at a predetermined fast speed when disposed in either position.
15. In a mining apparatus, a wheeled truck frame, a mining machine swivelly mounted thereon operable to cut in different planes to which the axis of swiveling is perpendicular when supported in inverted positions, and means to swivel said machine relative to said frame from said machine at different speeds in opposite directions when disposed in either position.
16. In a mining apparatus, a wheeled truck frame, a mining machine having feeding mechanism swivelly mounted thereon operable to cut in different planes to which
- the axis of swiveling is perpendicular when supported in inverted positions, means for propelling said truck frame and to swivel said machine relative to said truck frame from said mining machine feeding mechanism at different speeds when disposed in either position.
17. In a mining apparatus, a wheeled truck frame, a mining machine swivelly mounted thereon operable to cut in different planes to which the axis of swiveling is perpendicular when supported in inverted positions, means to swivel said machine relative to said frame from said machine at different speeds in opposite directions when said machine is disposed in either position, and means to reverse said truck at any speed.
18. In a mining apparatus, a wheeled truck frame, a self-contained mining machine having feeding mechanism and swivelly mounted as a whole on said truck frame and operable to cut in different planes when supported in inverted positions, and means for selectively propelling said truck frame and to swivel said machine relative to said truck frame from said feeding mechanism at different speeds, including independently operable clutches, when said machine is disposed in either position.
19. In a mining apparatus, a wheeled truck frame, a self-contained mining machine provided with a fast and slow speed feeding mechanism and frictional controlling means for each feed, said mining machine being swivelly mounted as a whole on said truck frame and operable to cut at different planes when supported in inverted positions, and means to swivel said machine relative to said frame from said feeding mechanism at either speed and variants thereof when disposed in either position.
20. In a mining apparatus, a wheeled truck frame, a self-contained mining machine provided with a feed operating member journaled on a longitudinally extending axis swivelly mounted on said truck frame, and means to swivel said machine relative to said frame including transmission mechanism detachably connectable to said feed operating member.
21. In a mining apparatus, a wheeled truck frame, a self-contained mining machine provided with a feed operating member journaled on a longitudinally extending axis swivelly mounted on said truck frame, and means to swivel said machine relative to said frame including a transmission means clutched to said feed operating member.
22. In a mining apparatus, a wheeled truck frame, a unitary mining machine provided with feed operating member disposed on the longitudinally extending horizontal axis of the machine, and means to swivel said machine relative to said truck frame

including transmission means driven from said feed operating member.

23. In a mining apparatus, a wheeled truck frame, a unitary mining machine provided with fast and slow speed feeding mechanism swivelly mounted on said frame and dismountable therefrom for cutting on the mine bottom, and means to swivel said machine relative to said truck frame including transmission means driven from said feeding mechanism.

24. In a mining apparatus, a wheeled truck frame, a unitary mining machine horizontally swingable thereon about a vertical axis and having slow feed mechanism, and swinging and truck driving mechanism driven by said feeding mechanism including a transmission shaft arranged coaxial with said axis.

25. In a mining apparatus, a wheeled truck frame, a unitary mining machine horizontally swingable thereon about a vertical axis and having slow feed mechanism, and swinging and truck driving mechanism driven by said feeding mechanism including a transmission shaft and cooperating gearing arranged coaxial with said axis.

26. In a mining apparatus, a truck frame, a unitary mining machine horizontally swingable thereon and having slow feed mechanism, and swinging and truck driving mechanism driven by said feed mechanism including a stationary bevel gear and a transmission shaft arranged coaxial with the machine axis.

27. In a mining apparatus, a truck frame, a unitary mining machine horizontally swingable thereon having slow feeding mechanism, and swinging and truck driving mechanism driven by said feeding mechanism including transmission mechanism hav-

ing an element fixed to said truck and a shaft arranged coaxial with the machine axis.

28. In a mining apparatus, a portable frame having a turntable and mechanism for effecting swinging movement thereof, a mining machine having opposed plane surfaces upon which it is disposable and constructed to cut when sliding directly upon the mine bottom upon either of such surfaces, and means to connect said machine in driving relation to said swinging mechanism when said machine is disposed in either position on said frame.

29. In a mining apparatus, a truck frame having running gear, a mining machine swivelly mounted thereon and having different surfaces on which it may be supported during operation and operable to cut in different planes when supported on said different surfaces, and self-contained means to swivel said machine relative to said frame actuatable by said machine when the latter is disposed upon said frame on any of said surfaces.

30. In a mining apparatus, a truck frame having running gear and swivel mechanism, a mining machine having different surfaces on which it may be supported during operation and operable to cut in different planes when supported on said different surfaces, and means to connect said machine in driving relation to said running gear to effect truck propulsion and to said swivel mechanism to effect swivelling upon the truck frame when said machine is disposed upon said truck frame with any of such surfaces in contact with said frame.

In testimony whereof I affix my signature.

MORRIS P. HOLMES.
